UNITED STATES PATENT OFFICE.

ARTHUR F. KRAKAUER, OF NEW YORK, N. Y.

DESIGN FOR A BATH-MAT.

41,194.

Specification for Design.

Patented Feb. 21, 1911.

Application filed December 21, 1910. Serial No. 598,670. Term of patent 7 years.

To all whom it may concern:

Be it known that I, ARTHUR F. KRAKAUER, a citizen of the United States of America, residing in the borough of Manhattan, city, county, and State of New York, have invented a new, original, and ornamental Design for a Bath-Mat, of which the following is a specification, reference being had to the accompanying drawing, forming part hereof.

The figure is a plan view of a bath mat showing my new design.

I claim—

The ornamental design for a bath mat as shown.

In witness whereof, I have hereunto signed my name in the presence of two subscribing witnesses.

ARTHUR F. KRAKAUER.
